UNITED STATES PATENT OFFICE.

NAPOLEON DU BRUL, OF CINCINNATI, OHIO.

DESIGN FOR A CIGAR-CUTTER.

SPECIFICATION forming part of Design No. 12,920, dated May 9, 1882.

Application filed June 1, 1881. Term of patent 14 years.

To all whom it may concern:

Be it known that I, NAPOLEON DU BRUL, of Cincinnati, Hamilton county, Ohio, have invented or produced a new and original Design 5 for a Cigar-Butt Cutter, of which the following is a specification, reference being had to the accompanying drawings, forming part thereof, in which—

Figure 1 is a front elevation. Fig. 2 is a top 10 view.

The leading feature of my design consists of the knife-holder here represented, in which, from a circular lower extremity, A, projects the represented arm or wing B, having circular swell C and a marginal bead, d d' , that encloses a sunk panel, E. This wing terminates in the semblance of an animal's head, F, with neck f and rounded back f' . From said head rises a projection, G. The holder has on its 15 rear face a marginal bead, H, (similar to the

bead d), hiding the blade g on the rear side. On the left side of the holder appears the portion of a circular disk, J, whose remaining portion is hidden by the holder. The rear journal-bearing, K, is of the represented U form, 25 as viewed from above, (see Fig. 2,) and appears as resting flatly upon the base, as indicated by dotted lines in Fig. 1.

I claim—

The design for a cigar-butt cutter herein 30 shown and described, the same consisting of the circular portions A and C, the wing B, having marginal bead d d' and sunk panel E, and the semblance of an animal's head, F, having the projection G and the rear marginal 35 head, H.

NAPOLEON DU BRUL.
